LATCH FOR HOSPITAL DOORS AND THE LIKE

Henry G. Voight, Hamden, Conn., assignor to
Sargent & Company, New Haven, Conn., a cor-
poration of Connecticut

Application November 17, 1943, Serial No. 510,622

1 Claim. (Cl. 292—170)

This invention relates to a latch for hospital doors or the like and more particularly to what may be termed "a push-pull latch" in that the latch bolt may be retracted by either a push or a pull action upon a handle or operating lever arranged at the outside of the door.

It is desirable to provide some form of latching device for hospital doors and the like to hold them in closed position. On the other hand, nurses and attendants desiring to open such doors often do not have their hands free to operate a knob or other door handle owing to the fact that they might be carrying articles in their hands which they do not wish to set down. Therefore, it is desirable to provide a handle or other operating member of the face of the door such that it may be operated by pressure of the arm or wrist, and it is also very advantageous that the operating member be movable in either direction to retract the latch bolt, that is to say that the latch bolt should be retracted by the movement of the handle either toward or away from the door. With such an arrangement, anyone desiring to enter a room may engage the door handle with the wrist or forearm and pull it toward himself, if the door opens in that direction, or push it toward the door if the door opens in the other direction, so that pressure in one direction or the other will both retract the latch bolt and serve to push or pull the door to open position.

It is contemplated by the present invention to provide a door with a latch bolt to retain it in closed position and provide, upon one or both faces of the door, an operating handle which will be provided with a free end spaced from the door so that this end may be engaged by the wrist or forearm upon either side, and provide connections between the handle and the latch bolt so that the bolt will be retracted whether the handle is pulled in a direction away from the door or pushed toward the door.

One object of the present invention is to provide a latch of novel construction for hospital doors or the like.

A still further object of the invention is to provide a latch for hospital doors or the like having a handle, pivotally mounted upon the face of the door and designed to be moved toward or away from the door, and connections between the handle and latch such that the latch will be retracted upon the movement of the handle in either direction.

A still further object of the invention is to provide a latch structure of the character described, wherein the handle mechanism will be duplicated

upon opposite sides of the door whereby the latch bolt may be retracted and the door opened from either side by a push-pull operation.

Still another object of the invention is to provide a door latch of the type described, wherein the handle, arranged at the outside of the door, is provided with a free end portion spaced from the door so that it may be engaged upon either side by the forearm or wrist of anyone desiring to open the door.

To these and other ends, the invention relates to the novel features and combinations of parts to be hereinafter described and claimed.

In the accompanying drawing:

Fig. 1 is an edge view of a portion of a door provided with a latch structure embodying my improvement;

Fig. 2 is a front elevational view of the latch structure and door handle;

Fig. 3 is a sectional view on line 3—3 of Fig. 2;

Fig. 4 is a sectional view on line 4—4 of Fig. 2;

Fig. 5 is a view of the latch bolt structure and casing with the cover of the casing removed to show the interior construction.

To illustrate a preferred embodiment of my invention, I have shown a portion of a door 10 having mounted therein a latch case 11 provided with a face plate 12, through which projects a latch bolt 13. The casing may be of general cylindrical form, as shown, so that it may be inserted in a bore provided through the edge of the door.

The bolt 13 is provided with a tail or stem comprising a pair of spaced platelike members 14 and 15, between which is disposed a spring 16 which acts against the bolt head at its forward end and against a post 17 at its rear end, the post being secured to the lock casing whereby the bolt will be urged to protracted position.

Between the members 14 and 15, and spaced rearwardly of the post 17, is rotatably mounted an anti-friction roller 18, this roller being carried by a pin 19 mounted in the spaced members 14 and 15 of the bolt stem. Rearwardly of the roller, these two members may be connected as at 20 to provide rigidity to the stem.

A bolt actuating member or bar 21 extends through the case 11 and is mounted to slide transversely of the case through openings 22 in the side walls thereof, these openings being slightly wider than the thickness of the actuating bar so that the latter may have a certain amount of vertical play. This bar is provided, adjacent its center, with a notch or recess 23 of general V-shaped form, within which the roller 18 nor-

normally lies. It will be obvious that, when the actuating bar 21 is moved in either direction transversely of the case 11 and of the direction of movement of the bolt 13, the roller 18 will be forced out of the recess 23 and thus the bolt will be cammed to retracted position. Upon release of the parts, however, the spring 16 will return them to their normal positions and the bolt to retracted position as the roller usually does not ride completely out of the recess.

The actuating member 21 extends through a bore 24 in the door and projects at each end from the face of the door at both sides thereof, the ends of the member being pivoted at 25 and 26 to bifurcated posts 27 and 28 secured to inner and outer handles 29 and 30. These handles are pivoted to the door adjacent one of their ends. As shown, they are pivoted at 31 and 32, adjacent their upper ends to posts 33 and 34, mounted on plates 35 and 36, respectively, secured to the inner and outer faces of the door. It will be noted that, at their lower portions, the handles 29 and 30 are provided with free ends 37 and 38 which are arranged in spaced relation to the inner and outer faces of the door so that one desiring to open the door may engage the inner or outer side of these handles. If desired, suitable trimming plates 39 and 40 may be provided about the bore 22, these plates having openings therein to register with the bore, which openings will be sufficiently large to receive the posts 27 and 28.

From the above description, it will be obvious that a person approaching the door from one side may engage the lower free ends of the handles 29 and 30 upon the outside thereof and push inwardly on these handles moving them toward the door, such movement serving to retract the latch through the movement of the actuating bar 21, and continued pressure upon the handle will serve to push the door to open position, provided, of course, that the door opens in the proper direction. If, however, the door opens in the opposite direction, the arm or hand is inserted between these lower ends of the handles and the door, and the handle is pulled outwardly away from the door, which movement will likewise

serve to retract the latch and move the door to open position. Thus, by the illustrated structure, the door may be opened from either side by either a pull action or a push action upon the free end of the door handle, depending upon the direction in which the door swings, and the handle may be moved by either the hand or the arm of the person desiring to enter the room.

Moreover, it will also be apparent in this structure that the actuating devices are bifurcated at each side of the door and operate in exactly the same manner. It will also be understood that, while the latch structure shown may be particularly useful in connection with hospital doors, it is also applicable to doors of other types and is not to be limited to use in connection with a door of any particular type.

While I have shown and described a preferred embodiment of my invention, it will be understood that it is not to be limited to all of the details shown but is capable of modification and variation within the spirit of the invention and within the scope of the appended claim.

What I claim is:

25 A door latch comprising a case, a bolt reciprocably mounted therein and normally projecting from the edge of the door, an operating bar slidably mounted in the case for movement in the direction of its length and transversely of the bolt, said bar being operatively connected to the bolt to retract the same when moved longitudinally in either direction and extending outwardly through the face of the door, a handle having one end pivoted to the door to swing toward and from the face thereof and having a post intermediate its ends which projects toward the door, said bar being pivoted to said post whereby movement of the handle moves said bar transversely of the bolt to retract the latter, the door having an opening to receive said post, and the free end of said handle being spaced from the door for manual engagement at either the inner or outer side thereof to facilitate movement of the handle either toward or from the door.

HENRY G. VOIGHT.
